UNITED STATES PATENT OFFICE.

TEIZO ISSHIKI, OF TOKYO, JAPAN, ASSIGNOR TO GENERAL ELECTRIC COMPANY, A CORPORATION OF NEW YORK.

INSULATOR TESTER.

Application filed July 13, 1925, Serial No. 43,108, and in Japan November 10, 1924.

My invention relates to apparatus for testing insulators while they are in use and has for its object a portable tester which is compact, accurate and reliable.

- 5 In carrying my invention into effect I employ apparatus which utilizes the static voltage existing on the insulator while in use. A suitable contact pole upon which is mounted a condenser is used to connect the 10 insulator to be tested to ground through such condenser. A portion of the static voltage across the condenser is applied to the grid of a vacuum tube detector and a measuring instrument or other current detector is connected in the plate circuit of the tube. In 15 certain cases amplification of the detecting current may be desirable. The apparatus is preferably made up in portable form so that it may easily be carried about for field use.
- 20 The features of my invention which are believed to be novel and patentable will be pointed out in the claims appended hereto. For a better understanding of my invention, reference is made in the following description 25 to the accompanying drawing; in which Fig. 1 is a connection diagram of a device embodying my invention; Fig. 2 is an enlarged cross-sectional plan view of the contact pole taken on the line 2-2 of Fig. 1; 30 Figs. 3 and 4 represent curves showing the relation between the grid-voltage and plate current of the vacuum tube detecting apparatus; and Figs. 5 and 6 are connection diagrams respectively where amplifiers are 35 used. The same reference numerals represent the same or similar portions throughout the drawing.

Now referring to Fig. 1 which is an embodiment of my invention, the contact pole is 40 provided with a handle of non-conducting material 1 with an insulator 2 at its end and a contact piece 3 fitted into the top of the insulator 2. A metallic induction plate 4 is fitted on a part of the insulator surface along 45 its circumference and another metallic induction plate 6 is placed around the external periphery and separated from plate 4 by an insulating layer 5, thus constituting a condenser. To the induction plates described 50 above are connected the conductors 7 and 8 respectively. A sufficient dielectric strength should be maintained between the contact piece 3 and the induction plates to guard against the working voltage of the transmission line, and it is preferable to have the

conductor 7 insulated, or otherwise protected from static effects of any body other than the contact piece 3.

If the contact piece 3 is brought into contact with the conductor between the insulator section (to the metallic connection in case of suspension insulators and to the cement in case of pin type insulators) and if the terminal of the conductor 8 is grounded, a voltage is impressed between the contact piece and induction plate 6 equal to that between the contact point and earth, and a voltage will be statically induced between the induction plates. The amount of the voltage between the induction plates will be equal to the product of the voltage between the contact point and ground and the ratio of electric capacity between the contact piece and induction plate 6 and the electric capacity between both induction plates. This voltage is proportional to the voltage between the contact point and ground, and may be altered by changing the relative spacing of contact piece 3, plate 4 and plate 6. 11 and 12 are variable condensers which operate to reduce the voltage between the terminals 9 and 10 of conductors 7 and 8 if desired and to apply it to the grid of a three electrode vacuum tube 15. 13 and 14 are leakage resistances for said condensers and are used only when they are necessary. The three electrode vacuum tube 15 can be regulated by a suitable adjustment of plate potential, filament current and negative grid bias potential V_g , so that when there is no voltage between terminals 10 and 9, the conditions of the tube will correspond to point P of Fig. 3 that is the plate current is of about zero value. When the alternating current voltage induced between terminals 9 and 10 is suitably stepped down to V_i and is impressed on the grid of the vacuum tube, the current corresponding to O'P' of Fig. 3 will flow in the plate circuit during the half cycle in which said voltage is positive with respect to the filament, and no current will flow through the plate circuit in the negative half cycle. Accordingly direct current ammeter 16 in the plate circuit will indicate the average value of the current O'P' flowing during positive half cycles, which value is a function of V_i , and is proportional to the induced voltage between the induction plates 4 and 6. Now, by adjusting the voltage V_g produced by the battery 21 so that the maximum value of V_i will not sur-

pass the grid biasing voltage V_G , a plate current corresponding to V_G will flow, but without any flow of grid current, whereby the induced voltage between terminals 9 and 10 can be measured without the disturbance of the three electrode vacuum tube.

The process of detecting defective insulators by the apparatus of my invention is as follows: The tip of contact piece 3 should be touched to the transmission line 17 to find out the indication of the ammeter and then compare it with the indication obtained by bringing the tip contact 3 to the connection 18 above the first section 19 of the insulator string. Since the indication of ammeter 16 obtained from the transmission line corresponds to the voltage between the transmission line and earth, the voltage at point 18 should be considerably below that at point 17 if the first section is sound, while if it is defective the difference will be very small and thus detected at once. In this procedure it is necessary to measure the indication of the ammeter previously on a perfect insulator, and a certain standard obtained for the purpose of judgment. Then the tip of contact piece 3 should be shifted to the point 20 and the same procedure repeated.

If the current in the plate circuit of the three electrode vacuum tube is small the current can be amplified by using three electrode vacuum amplifier 15' as shown in Fig. 5 or by amplifying in several steps, such for instance as three steps as shown in Fig. 6; in these figures the transformer connections between the tubes are representative of one of several possible connections. In such cases the grid potential of the first three electrode vacuum tubes need not be so adjusted, when there is no voltage between terminals 9 and 10, that it corresponds to the point P of Fig. 3, that is, its plate current need not be zero, but it is preferable to be adjusted to correspond with the point Q, Fig. 4. The grid voltage of the last amplifier may then be so adjusted that it corresponds with the point P of Fig. 3 when the ammeter 16 is directly inserted in the plate circuit. The ammeter may be connected through a transformer 22 as indicated at the right of Figs. 5 and 6 in which case the last amplifier may be adjusted to correspond to point Q of Fig. 4. In the former case the ammeter may be either a direct current or an alternating current instrument and in the latter case it must be an

alternating current instrument. Any other type of current detector may be employed in place of an ammeter.

In accordance with the provisions of the Patent Statutes, I have described the principle of operation of my invention, together with the apparatus which I now consider to represent the best embodiment thereof, but I desire to have it understood that the apparatus shown and described is only illustrative and that the invention may be carried out by other means.

What I claim as new and desire to secure by Letters Patent of the United States, is:

1. Apparatus for testing insulators comprising a multiple plate condenser arranged to be connected between the insulator to be tested and ground, a three-electrode vacuum tube having grid and plate circuits, a current detector for detecting the flow of current in the plate circuit of said tube, and variable condenser apparatus connected in parallel with a portion of said first mentioned condenser for applying an adjustable voltage proportional to the static voltage of said insulator to the grid of said tube. 75 80

2. A portable insulator testing apparatus comprising a multi-plate condenser mounted upon a pole and having terminals for connecting the condenser between an insulator to be tested and ground, a three-electrode vacuum tube having grid and plate circuits, means for measuring the current in the plate circuit of said tube, and a circuit including static voltage adjusting means for impressing a voltage proportional to the voltage across said condenser upon the grid of said vacuum tube. 85 90

3. In apparatus for testing insulators, a pole of non-conducting material, a cylindrical insulator on one end of said pole, a contact rod embedded in said insulator and extending therefrom in an axial direction, a metallic plate along one circumference of said insulator, and a cylindrical conductor 100 surrounding said parts and separated from said plate by a layer of insulation, said parts forming a three-plate condenser from which a static voltage less than but proportional to a static voltage charge between said contact rod and cylindrical conductor may be obtained. 105

In witness whereof, I have hereunto set my hand this twentieth day of June, 1925.

TEIZO ISSHIKI.
